The ornamental design for a blade for spiral wing shaft for mixers, as shown and described.

(30) **Foreign Application Priority Data**

DESCRIPTION

Dec. 17, 2003 (JP) 2003-037283

FIG. 1 is a front view of a blade for spiral wing shaft for mixers showing our new design;

(51) LOC (8) Cl. **15-03**

FIG. 2 is a rear view thereof;

(52) U.S. Cl. **D15/19; D15/28**

FIG. 3 is a top plan view thereof;

(58) Field of Classification Search D15/17,

D15/19, 21, 28, 29, 32, 11; 366/341, 343,

366/57, 59, 45, 227, 229, 64, 325, 320, 603

FIG. 4 is a bottom plan view thereof;

See application file for complete search history.

FIG. 5 is a right side view thereof;

(56) **References Cited**

FIG. 6 is a left side view thereof;

U.S. PATENT DOCUMENTS

FIG. 7 is a cross-sectional view taken along line 7—7 in FIG. 6; and,
